UNITED STATES PATENT OFFICE.

EUGENE D. JEFFERSON, OF BOSTON, MASSACHUSETTS.

VOMITING-KEIR.

1,278,154.

Specification of Letters Patent. Patented Sept. 10, 1918.

Application filed December 29, 1916. Serial No. 139,580.

To all whom it may concern:

Be it known that I, EUGENE D. JEFFERSON, a citizen of the United States, residing at Boston, in the county of Suffolk and State 5 of Massachusetts, have invented certain new and useful Improvements in Vomiting-Keirs; and I do hereby declare the following to be a full, clear, and exact description of the invention, such as will enable others 10 skilled in the art to which it appertains to make and use the same.

This invention relates to an improvement in vomiting keirs. The object of the invention is to reorganize and improve the construction of vomiting keirs. Certain features of the invention relate to improvements of construction of the vomiting keir illustrated and described in the patent granted to me November 22, 1904, No. 20 775,450.

In mills or bleacheries where these keirs are used, they are ordinarily arranged in batteries, with a floor near the top of the cylindrical portion of the keirs for convenience in bringing materials to and taking them from them. Each keir had separate automatic mechanism for opening and closing the motive steam valve, which, because of its functional relation to the keir, was necessarily located near the bottom of the keir. One simplification which the present invention contemplates is providing a single mechanism for operating the valves of an entire battery of keirs. Thus the controls for the battery of keirs are banked together in a single unit, which may be conveniently located above the floor line and therefore easy of access. One feature of the invention resides in this banking of the keir 40 controls.

It will be noted that in the keir of the said patent, the automatic means for opening and closing the motive steam valve is located in the bottom of the pit near the keir. All of 45 its parts are, therefore, exposed to the action of the liquor, which necessarily subjects them to severe working and wearing conditions. According to the present invention, the greater portion of the operative parts of 50 the keir, such as valves and mechanism, are raised above the liquor line, so as to improve the wearing conditions and prolong the life of the parts. Not only does this increase the durability of the apparatus, but it increases economy of operation by reducing

the time necessarily required to operate the keir.

In the keir of the said patent the automatic means for opening and closing the motive steam valve is actuated to be opened and closed as a result of a rise or fall of the level of the liquor in the trap, and therefore the vomiting action is dependent upon the rate of flow or seepage of the liquor through the materials, so that a substantially uniform amount of liquor is vomited into the top of the keir at intervals dependent upon its rate of collection. According to the present invention, the vomiting action takes place at uniform intervals of time, irrespective of the amount of liquor which has seeped or flowed into the trap. While excellent results were obtained by the use of the mechanism of the said patent, it has been found that superior results are obtained by making the vomiting action positive and dependent upon a timed interval rather than upon the flow of liquor through the materials. One reason for this is believed to be due to the fact that the flow of liquor into the top of the keir is more frequent and gentle, instead of being more infrequent, sudden and more or less violent. Incidentally, the present invention subjects the operating parts, such as valves and other elements, to considerably less wear, and avoids hammer and incident deterioration.

One of the important advantages of the present construction resides in the diminished steam consumption, conducing to its economy of operation. In addition to the foregoing features and advantages of the present construction, it is to be observed that the mechanism is simpler, and this also commends it to users.

In the accompanying drawings, Figure 1 is a sectional elevation illustrating a single keir, and a single controlling means; Figs. 2 and 3 illustrate, respectively, a front and sectional end elevation of a banked control for a battery of 8 keirs; Fig. 4 is a detail hereafter referred to; and Fig. 5 is a diagrammatic illustration of a battery of keirs provided with a banked control.

The illustrated embodiment of the invention is described as follows:—The keir proper 1 consists of the usual sheet metal vessel provided with a removable cover 2 secured by bolts in the usual manner at the top. In the keir is the usual grid or grate 3 110

on which the materials to be treated are laid. The vomiting pipe consists of a pipe and suitable connections forming a closed passage connecting the top and bottom of the keir. This vomiting pipe is indicated in a general way by the reference character 4, which is intended to designate the pipe as a whole. A portion 5 of the vomiting pipe, extending from the bottom of the keir, leads 5 through the check valve 6, which prevents back-flow of liquor into the bottom of the keir. The pipe 5 discharges into the bottom of a trap 7 which is made considerably larger than the vomiting pipe proper and sufficient 10 to hold a considerable body of liquor. Into the trap 7 depends a pipe 8 which extends up through the top of the trap 7 and to the check elbow 9. A pipe 10 leads from the elbow 9 to the T 11 which discharges into the 15 keir in the usual manner. The liquors percolating through the materials in the keir find their way through the pipe 5 and check valve 6 into the trap 7 where they collect and remain until discharged into the top of 20 the keir. The liquor is forced up through the vomiting pipe by means of steam pressure, a motive steam pipe 12 being provided, which discharges live steam into the top of the trap 7 at regular intervals of time. The 25 steam supply pipe 13 leads steam through the T 14 to the hand valve 15, and thence to the automatically controlled valve 16, from which it flows through the elbow 17 to the pipe 12 in which is located a second hand 30 valve 18. From the T 14 a branch pipe 19 leads through the valve 20 to the vomiting pipe 10 and affords means for admitting steam to the keir for the purpose of heating it. A vent pipe 21 leads from the top of the 35 trap 7 to the check elbow 9, and affords limited free communication between the top and bottom of the keir at all times, so as to equalize the pressures and allow the liquor 40 freely to flow into the trap 7. The vent pipe 21 is small, and does not materially reduce the pressure exerted by the steam upon the liquor in the trap, but it is sufficiently large to permit the steam to escape from the trap after the motive steam valve has been closed; 45 it is provided with a check valve opening 50 toward the top of the keir at its upper end. The automatically controlled valve 16 is operated by means of an electric motor 22, which, through reducing gearing, opens and 55 closes the valve 16 from time to time during the progress of the boiler operation. The motive steam valve is shown in Figs. 2, 3 and 4, and will be described in connection with the description of the banked control illustrated in those figures. It is sufficient here to note that the motor 22 is supported upon a pedestal 23 conveniently mounted on the elbow 17. The steam gage 24 indicates the 60 pressure of the motive steam, and the steam gage 25 indicates the pressure in the keir.

The floor 26 is located near the top of the cylindrical portion of the keir, and all of the hand valves and automatic mechanism for operating the keir are located above this floor level—in fact, the only valve below the 70 floor is the check valve 6 which necessarily is required to remain in position at the bottom of the keir.

The operation of the apparatus is substantially the same as the operation of the apparatus of said patent, except that the opening and closing of the motive steam pipe is performed at timed intervals instead of at intervals dependent upon the rise and fall of the liquor level in the trap. Briefly, the 75 operation is described as follows:—When the liquor in the keir flows out into the vomiting pipe, it gradually rises in the trap 7 until the motive steam valve 16 is opened, and then live steam is admitted through the 80 pipe 12 to the top of the trap, and the pressure exerted by the steam on the liquor in the trap closes the check valve 6 and forces liquor out of the trap up through the vomiting pipe 4 and into the top of the keir as long as 85 the motive steam valve remains open. When the motive steam valve closes, the pressure falls in the trap, and the flow of liquor from the keir into the trap is resumed.

The mechanism of the banked control is 90 described in connection with Figs. 2, 3, 4 and 5 as follows:—The main steam supply pipe 50 consists of a riser, which is connected at its lower end with the steam main or boiler and at its upper end with a multiple T having as many discharge pipes 51 as there are keirs. Each discharge pipe 51 is controlled by a hand valve 52, an automatically controlled valve 53, and a second hand valve 54 on the keir side of the valve 100 53. The valves 52 and 54 are the usual steam valves. The valve 53 is associated with each keir, and it is opened and closed at timed intervals to admit steam to the trap of the particular keir which it serves. 105 In Fig. 3 a section of the valve is shown. The valve member 60 is integral with the stem 61 which is normally held in raised position by the spring 62, a cover 63 being provided for insertion and removal of the 110 valve and stem. The valve stem 61 projects upwardly through the stuffing box 64 and is screwthreaded upon its upper end at 65. A nut 66, provided with an upwardly 115 extended stem 67, is screwed on to the upper end of the valve stem 61 and held in place by a lock nut 68. A valve slide 70 is provided with a socket 71 which receives the stem 67 of the nut 66. This valve slide 120 70 is depressed at regular intervals, and when depressed, it pushes down the valve stem and opens the motive steam valve 53. When it rises, the steam valve is closed by its spring. The valve slide carries a timer 125 gib 72, which consists of a right-angled 130

piece of steel secured to the valve slide, in the manner shown, by the stud bolts 73. The upper surface 74 of the gib is engaged by pins 75 mounted in a timer wheel 76. 5 This timer wheel 76 rotates in the direction of the arrow 77, and the pins 75 strike the timer gib and depress the valve slide 70, thereby opening the valve. When a pin 75 passes beyond the end of the timer gib 72, 10 the valve closes. It will be noted that by adjusting the timer gib to the left, as seen in Fig. 4, the duration of the opening of the valve 53 will be shortened, and that by adjusting it to the right, the duration of the 15 opening will be lengthened. It will also be noted that the amount of valve lift may be adjusted by loosening the check nut 68 and turning the nut 66 up or down as desired. The upper end of the valve slide 70 is forked, 20 as shown in Figs. 3 and 4, and embraces the time shaft 78 by which it is steadied. Pivotally mounted on the valve slide is a latch 80 provided with a ball handle 81 by which it is manipulated by the operator. The 25 right-hand end 82 of the latch, as seen in Fig. 4, is forked, and in the position shown in Fig. 4, it is inserted in the space between the lower end of the valve slide and the upper surface of the nut 66. With the latch 30 in this position, the timer gib on the valve slide is lifted high enough to be engaged by the pins 75; and when the forked end 82 of the latch is withdrawn from between the lower end of the valve slide 70 and the upper 35 surface of the nut 66, the slide is permitted to fall a distance equal to the thickness of the fork 82 of the latch, so as thereby to lower the valve slide a distance sufficient to bring the timer gib below the path 40 of motion of the pins 75. By this construction the motive steam valve may be thrown out of operation, although the timer wheel continues to run. All of the timer wheels 76 are mounted side by side on the time shaft 45 78, as shown in Fig. 2, and any one or all of the steam valves 53 may be thrown out of operation or into operation at pleasure, without interfering with any other valve. On the left-hand side of Fig. 2 the valves 50 54 are shown in position; on the right-hand side of this figure these valves 54 have been omitted for clearness of illustration of the valves 53.

By reference to Fig. 3, it will be seen that 55 the timer wheel 76 is provided with six holes to receive the pins 75. When one pin only is inserted in one of the holes, as 90 for example, there will be one opening of the valve 53 at each revolution of the timer wheel. When the holes 90 and 93 are provided with pins 75, there will be two openings of the valve for each revolution of the timer wheel. When holes 90, 92 and 94 are provided with pins, there will be three openings 60 of the valve 53 for each revolution of the timer wheel. When pins are provided in the holes 90, 91, 93 and 95 there will be four openings of the valve 53 during each revolution of the timer wheel. This affords a convenient means for timing 70 the opening of the motive steam valves.

The time shaft 78 is mounted in bearings 100 which are supported from a shelf 101, carried by the bracket 102 mounted on the wall or otherwise. The time shaft 78 is provided with a worm wheel 103 which is driven by a worm 104 mounted on a shaft 105 supported in bearings 106 carried by the shelf 101. A worm wheel 107 is mounted upon the shaft 105 and driven by a worm 108 80 mounted on the worm shaft 109 which is adapted to be coupled by clutches to the motor 110, or the motor 111. A lever 112 pivoted at 113 is provided to shift the clutches so as to connect the worm with either motor. 85 The motors are supported on the blocks 114, which are bolted to the shelf 101. Suitable switches for the motors have provision for running either the one motor or the other, as may be desired, so that in case of breakdown of one motor, the other motor may be used, or one motor may be rested while the other motor is used. The operating devices for each of the valves 53 are identical with the operating devices for the valve 16 in the 90 single keir unit, such as is shown in Fig. 1.

In Fig. 5 is shown, in a diagrammatic way, a battery of keirs K and a single banked control C for the keirs. The simplicity of the arrangement and its obvious efficiency 95 are apparent. This banked control for a battery of keirs reduces the mechanism required for operating the keirs very materially, and has proved very satisfactory in use. Each valve 53 bears a number, which corresponds to the number of a keir, and when it is desired to throw any keir into and out of operation, the manipulation of the latch of the appropriate valve throws the keir into or out of operation, as desired.

Having thus described the invention, what is claimed is:

1. A vomiting keir having, in combination, a closed keir adapted to contain liquor under pressure, a closed vomiting pipe connecting the bottom and the top of the keir, and means operating at timed intervals for raising the liquor from the bottom to the top of the vomiting pipe independently of the pressure in the keir.
2. A vomiting keir having, in combination, a keir, a vomiting pipe connecting the bottom and the top of the keir, a trap connected with the vomiting pipe, means for raising liquor from the trap through the vomiting pipe to the top of the keir, and time-controlled means for controlling the operation of the liquor-raising means.
3. A vomiting keir having, in combination, a keir, a vomiting pipe connecting the bot-

tom and the top of the keir, a trap connected with the vomiting pipe, means for raising liquor from the trap through the vomiting pipe to the top of the keir, and time-controlled means for controlling the operation of said liquor-raising means located above the liquor line in the keir.

4. A vomiting keir having, in combination, a keir, a closed vomiting pipe connecting the bottom and the top of the keir, a trap connected with the vomiting pipe, a motive steam pipe connected with the trap to admit steam thereto to force liquor from the trap through the vomiting pipe into the top of the keir, and time-controlled means operating independently of the pressure in the keir for controlling the flow of steam into the trap.

5. A vomiting keir having, in combination, a keir, a closed vomiting pipe connecting the bottom and the top of the keir, a trap connected with the vomiting pipe, a motive steam pipe connected with the trap to admit steam thereto to force liquor from the trap through the vomiting pipe into the top of the keir, and time-controlled means for controlling the flow of steam into the trap operating independently of the pressure in the keir to admit steam at timed intervals into the trap.

6. A vomiting keir having, in combination, a keir, a vomiting pipe connecting the bottom and the top of the keir, a motive steam pipe connected with the vomiting pipe, and mechanism operating independently of the pressure in the keir to open and close the motive steam pipe at timed intervals.

7. A vomiting keir having, in combination, a keir, a vomiting pipe connecting the bottom and the top of the keir, a trap connected with the vomiting pipe, a vent pipe connecting the top of the trap with the top of the keir, a motive steam pipe connected with the trap, and intermittently operating time-controlled mechanism to open and close the motive steam pipe.

8. A vomiting keir having, in combination, a keir, a vomiting pipe connecting the bottom and the top of the keir, a motive steam pipe connected with the vomiting pipe, and means located above the liquor line for opening and closing the motive steam pipe.

9. A vomiting keir having, in combination, a keir, a vomiting pipe connecting the bottom and the top of the keir, a motive steam pipe connected with the vomiting pipe, and power means for opening and closing the motive steam pipe at timed intervals.

10. A vomiting keir having, in combination, a keir, a vomiting pipe connecting the bottom and the top of the keir, a motive steam pipe connected with the vomiting pipe, a valve in the motive steam pipe, and power means for opening and closing the valve,

having provision for disengagement therefrom.

11. A vomiting keir having, in combination, a keir, a vomiting pipe connecting the bottom and the top of the keir, a motive steam pipe connected with the vomiting pipe, a valve in the motive steam pipe, and power means for opening and closing the valve.

12. A vomiting keir having, in combination, a keir, a vomiting pipe connecting the bottom and the top of the keir, a motive steam pipe connected with the vomiting pipe, a valve in the motive steam pipe, and power means for opening and closing the valve, having provision for regulating the duration of the opening of the valve.

13. A vomiting keir having, in combination, a keir, a vomiting pipe connecting the bottom and the top of the keir, a motive steam pipe connected with the vomiting pipe, a valve in the motive steam pipe, and power means for opening and closing the valve, having provision for regulating the frequency of the opening of the valve.

14. A vomiting keir having, in combination, a keir, a vomiting pipe connecting the bottom and the top of the keir, a motive steam pipe connected with the vomiting pipe, a valve in the motive steam pipe, and power means for opening and closing the valve, having provision for regulating the amount of the opening of the valve.

15. A vomiting keir having, in combination, a keir, a vomiting pipe connecting the bottom and the top of the keir, a motive steam pipe connected with the vomiting pipe, a valve in the motive steam pipe, power means for opening and closing the valve, and means for disengaging the valve from the operating means.

16. A vomiting keir having, in combination, a keir, a vomiting pipe connecting the bottom and the top of the keir, a motive steam pipe connected with the vomiting pipe, a valve in the motive steam pipe, power means for opening and closing the valve, having provision for regulating the duration of the opening of the valve and means for disengaging the valve from the operating means.

17. A vomiting keir having, in combination, a keir, a vomiting pipe connecting the bottom and the top of the keir, a motive steam pipe connected with the vomiting pipe, a valve in the motive steam pipe, power means for opening and closing the valve, having provision for regulating the frequency of the opening of the valve and means for disengaging the valve from the operating means.

18. A vomiting keir having, in combination, a keir, a vomiting pipe connecting the bottom and the top of the keir, a motive

steam pipe connected with the vomiting pipe, a valve in the motive steam pipe, power means for opening and closing the valve, having provision for regulating the amount of the opening of the valve and means for disengaging the valve from the operating means.

19. A battery of vomiting keirs having, in combination, a plurality of keirs, a vomiting pipe connecting the bottom and the top of each keir, a banked control, motive steam pipes connecting the banked control with the vomiting pipe of each keir, valves in said pipes, power means for opening and closing the valves, and means having provision for disengagement of any valve from the power means.

20. A battery of vomiting keirs having,

Copies of this patent may be obtained for five cents each, by addressing the "Commissioner of Patents, Washington, D. C."

in combination, a plurality of keirs, vomiting pipes connecting the bottom and the top of each keir, a banked control for the keirs comprising a steam supply pipe running to the control, motive steam pipes running from the control to each vomiting pipe, valves in said steam pipes, and power means for opening and closing the valves at timed intervals.

21. A battery of vomiting keirs having, in combination, a plurality of keirs, a vomiting pipe connecting the bottom and top of each keir, a banked control for the keirs comprising means for raising liquid from the bottom to the top of the pipes independently of the pressure in the keir.

EUGENE D. JEFFERSON.
